UNITED STATES PATENT OFFICE.

CARBON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA.

PROCESS FOR TREATING HYDROCARBON OILS.

Application filed June 3, 1922. Serial No. 565,684.

To all whom it may concern:

Be it known that I, CARBON P. DUBBS, a citizen of the United States, and residing in the city of Wilmette, county of Cook, and 5 State of Illinois, have invented certain new and useful Improvements in Processes for Treating Hydrocarbon Oils, of which the following is a specification.

This invention relates to a method for 10 treating hydrocarbon oils to produce therefrom products having lower boiling points.

This application is a continuation in part of an application Serial No. 204,527 filed November 30th, 1917.

15 Among the salient objects of the invention are to provide an improved process in which the heated hydrocarbons are circulated through a heating coil and into and through a coil still, and then passed to a condenser, and during such treatment subjected to a pressure of the generated vapors; to provide a process in which the rate of circulation in the coils of the oil, its temperature and pressure, are readily and accurately 20 controlled; to provide a process which can be operated continuously; to provide a process which avoids the danger of the heating tubes being burned out by precipitation of carbon, by means of circulating the oil 25 through said tubes; to provide a process in which such products that are only partly converted to the desired low boiling point are returned and further circulated through the heating tubes; to provide a process where 30 by means of controlled air cooled condenser, the grade of distillate allowed to pass from the system is controlled and such distillate not up to a desired grade is condensed and automatically returned to the distilling 35 coils and redistilled; to provide a process in which heating tubes are maintained in a furnace within well defined temperature ranges, and the oil caused to circulate in each set of heating tubes; to provide in general, an improved process of the character 40 referred to.

Fig. 1 and Fig. 1^a together show the side elevation of the apparatus partly in section and with other parts broken away.

45 Fig. 1^b is a fragmentary detail view of a liquid level device.

Fig. 2 and Fig. 2^a are a plan view of the construction shown in Fig. 1 and Fig. 1^a.

50 Fig. 3 is a detail view of one of the condenser members.

Fig. 4 is a view partly in end elevation and partly in section of the heating coils.

Referring to the drawings, A¹ are furnaces in which the heating tubes are positioned. A² is a tunnel through which the fire for heating the furnaces passes. A³ is a flue tunnel. A⁴ is a flue and stack.

B¹ constitute parallel substantially level heating tubes and B² constitute parallel substantially level distilling tubes. B³, B⁴, B⁵ and B⁶ are return T's on the heating tubes. B⁷, B⁸ and B⁹ are return T's on the distilling tubes. B¹⁴ and B¹⁵ are bands around the tubes for anchoring the particular heating tubes shown. With the exception of the 70 said anchors the tubes extend freely through the furnace walls and can expand independently thereof. B¹⁶ and B¹⁷ are braces for supporting the tubes B¹ and B².

C¹ is a feed line from any source of supply 75 to pump C², and in this line is throttle valve C³. C⁴ is a charging line to heating tubes B¹, and in this line is throttle valve C⁵. C⁶ and C⁷ are motors for operating the pumps C² and C⁸. C⁸ is a pump which is supplied 80 through line C⁹ branch from line C¹. C¹⁰ is discharge line connecting this pump with charging line C⁴ and branching off of discharge line C¹⁰ is a branch line C¹¹ which connects with suction line C⁹ and having positioned on it a pressure relief valve or bypass valve C¹². C¹³ is a meter of any standard make suitable for the work in hand. C¹⁴ is a standard make check valve. C¹⁵ is an automatic liquid level regulating gauge, and the one shown here is that which is furnished 90 by "S-o" Regulator Company of Fostoria, Ohio, and C¹⁵ shown attached to the end of distilling tubes B² operates to open and close the regulator C¹⁶, which regulator is connected with C¹⁵ by a diaphragm C¹⁷, diaphragm C¹⁷ being positioned in the supply line C⁴. It will be understood that any suitable method may be employed for regulating 95 the level in the distilling tubes B². As this regulator is of standard equipment and operates on well known principles and the valve operated by a diaphragm is of standard make and well understood, I have not gone into the description of same here, nor do I claim any part of the regulator itself as new.

B¹⁸ is a fitting connecting adjacent heating tube B¹ to the supply line C⁴. B¹⁹ is the fitting on the end of the heating tube B¹ through which the oil in same is discharged 100 105 110

into line D¹. This line D¹ is connected to the bottom of the fitting B¹² which is secured to the distilling tubes B². The oil is discharged out through the bottom of the fitting B⁸ by means of line E¹ and through cooling tank E² and then to any suitable storage, not shown, and between said storage and cooling tank E² is positioned in line E¹ a throttle valve E³ to control the rate of flow of the residuum from the line E¹; and a similar throttle valve E⁴ is positioned in the line E¹ for obtaining samples of residuum from said line E¹.

F¹ is a centrifugal pump. F² is a motor for operating same. F³ is a suction line to the pump from the distilling tubes B² coming out of the bottom of the fitting marked B¹³. F⁴ is discharge line which enters the side of the fitting B¹² on the end of the tube marked B². F⁵ is a carbon trap on the bottom of the suction line as it comes out of the fitting B¹³. F⁶ is also a centrifugal pump. F⁷ is a motor for operating same. F⁸ is a suction line to the pump from the heating tubes B¹ coming out of the bottom of the fitting marked B⁶. F⁹ is a discharge line from the pump which enters the side of the fitting marked B¹⁰ on the end of the tube B¹. It will thus be seen that the oil introduced to the heating tubes B¹ and the distilling tubes B² may be independently circulated in either or both of said sets of tubes, attention being called to the fact that this circulation through the tubes B¹ may be independently carried out by operating the pump F⁶, which draws oil through the pipe connection F⁸ through the pump F⁶, the connection F⁹ and into one of the tubes of the heating coil B¹. A local or independent circulation may be also separately maintained in the distilling tubes B², through the agency of the pump F¹ connected with the pipes F³ and F⁴. Small quantities of raw oil may be introduced to the heating tubes B¹ during the independent cyclic circulation in the heating zone and manifestly an independent circulation may be maintained in both the heating and the distilling zone simultaneously, or a circulation maintained in one zone without causing a circulation in the other.

G¹, G², G³ and G⁴ are upwardly inclined vapor lines leading off of the distilling tubes B². Lines G¹ and G⁴ connect with a manifold G⁵, which manifold connects by pipe G⁶ to a fitting B⁸ attached to the distilling tubes B². Lines G² and G³ connect to manifold G⁷, which manifold connects by means of pipe G⁸ to the top of fitting B¹³ on the end of the distilling tubes B². These vapor lines G¹, G², G³ and G⁴ are connected at upper end to a common header G⁹ and have positioned on them throttle valves G¹⁰, G¹¹, G¹² and G¹³. Said manifold G⁹ is connected

to a top manifold G¹⁴ by means of bent pipes G¹⁵ to G²⁶; and to the center of the top manifold G¹⁴ is connected pipe G²⁷ which connects in turn to coils G²⁸ contained in water tank G²⁹. From coils G²⁸, the condenser pipe extends through pipe G³⁰ into receiving tank H. From pipe G³⁰ is a branch pipe G³¹ having a pressure indicating gauge G³², and out of the pipe G³¹ extends pipe G³³ on end of which is a valve marked G³⁴. This valve and gauge may be situated in the tail house and affords means for there regulating the pressure.

On tank H are glass liquid gauges H¹ and H², pressure relief valve H³, draw-off valves H⁴, H⁵ and H⁶ and pressure gauge H⁷. H⁶ is for use in case water is to be drawn off before draining the distillate out through valve H⁵. H⁴ is a valve for use in an emergency, for example, when one of the other valves are removed for repair or renewal and is unnecessary for showing the workings of the apparatus.

J¹, J², J³ are supports for the receiving tank H. K is a support for the pipes as shown.

L¹ is a standard indicating pyrometer and is connected with different thermo-sticks, which thermo-sticks are positioned in the furnace in which the tubes B¹ and B² are positioned. L² is a standard temperature recording instrument and connected to a thermo-stick by a cable, and which thermo-stick is positioned inside the manifold G¹⁴. L³ is a standard temperature recording instrument connected to thermo-sticks, which latter are positioned, one in the heating coils to give the temperature of the oils therein, and one positioned in the large distilling coils, to give the temperature therein. L⁴ is a standard level indicating gauge, which is connected by tubing to the receiving tank H and shows the depth of the liquid contained in receiving tank H. L⁵ is a standard switchboard, which board contains a standard knife switch for breaking or completing the circuit for operating the charging pump C²; also a knife switch for completing or breaking the circuit for controlling the motor C⁷, which operates the circulating pump C⁸, also a knife switch for breaking or completing the electric current for controlling the electric circulating pump F¹; also a knife switch for breaking or completing the electric current for the electric lights in the plant, all of which are enclosed in a house built beneath the water cooling tank G²⁹.

M¹ is a gas main for supplying the furnaces in which tubes B¹ and B² are contained.

N¹, N², N³ and N⁴ are supports for the extensions O¹ and O² which extensions are simply housing over the ends of the preheating tubes B¹ and the distilling tubes B²,

- which housing is to prevent more or less cooling effect that would be caused by leaving them open to the atmosphere and also to prevent subjecting the ends to varying temperatures.
- Describing now the operation of the process, the material to be treated is to be drawn from any suitable source of supply through line C¹ by and through centrifugal pump 10 C², through line C⁴ into heating tubes B¹. Then through line D¹ to distilling tubes B² and when these latter tubes have been filled to desired level, pump C² is shut down and valve C³ on line C¹ and valve C⁵ on line C⁴ are closed, and normally remain closed during the rest of the run. Heat is supplied to the furnace A¹ and as soon as a desired vapor pressure has been created on the apparatus, then supply pump C⁸ is started in 20 operation and obtains its supply of raw material through line C⁹ and discharges through line C¹⁰ into line C⁴, valve C¹⁸ being opened, and should the level of the liquid in the distilling tubes B² be of the proper 25 height, then the liquid level regulator C¹⁵ will by means of diaphragm C¹⁷, close the valve C¹⁶ on supply line C⁴, and the back pressure thus created on the line C⁴ will force open the pressure relief valve C¹² and 30 by-pass the oil from the discharge side of pump C⁸ back into the suction line C⁹, and this operation will continue until the level in the distilling tubes B² drops to a sufficient point to permit the valve C¹⁶ to be 35 automatically opened, thus admitting more raw material into the heating tubes B¹ and B².
- Pump F¹ is started and continues to operate during the process. This causes the oil 40 to circulate through the distilling tubes B². This is accomplished by drawing the oil through suction F³ and discharging it back into the tubes, through the discharge pipe F⁴.
- The residuum formed in the distilling tubes B² is drawn off either intermittently or 45 continuously through line E¹ through cooling coil contained in tank E² and from there to any suitable storage. The quantity of residuum drawn off from this coil is regulated by means of valve E³ positioned in the line E¹, and samples of said residuum may be obtained at any time through cock E⁴ in line E¹. Pump F⁶ is maintained in operation throughout the process, and the oil in heating tubes B¹, is thus made to circulate by drawing off the oil through suction pipe F⁸ and discharges back into these same tubes 55 through the discharge tubes F⁹.
- The vapors generated pass up through lines G¹, G², G³ and G⁴ and manifold G⁹ and from there up through pipes G¹⁵ to G²⁶ into manifold G¹⁴. All the vapors that are 60 condensed up to this point are drained back into the distilling tubes B² while the re-
- maining vapors pass up through line G²⁷ through coil G²⁸ immersed in water in tank G²⁹, and from there pass through line G³⁰ into receiving tank H from which they may be drawn off intermittently or continuously 70 through valves H⁴, H⁵ or H⁶.
- It will be seen that this method provides a process for automatically and continuously treating petroleum for the production of lower boiling point products and by 75 means of the independent circulation of the liquids in heating tubes B¹ and distilling tubes B² permits the furnace in which the tubes are positioned being maintained at a considerably higher heat without injurious 80 effect to the oil and in fact up to certain well defined limits, which limits are readily ascertained for any particular oil, it is of great commercial advantage to have the furnaces hotter than the oil contained in tubes positioned in furnace A¹ or oil and vapors contained in tubes B², and both maintained in rapid circulation through these tubes.
- The entire system is preferably subjected 85 to a vapor pressure of from 50 to 500 lbs. per square inch, although the pressure will vary with the conditions. The temperature of the oil will preferably vary from 500 to 1000 degrees Fahrenheit, although these limits are in no sense absolute. The pumps are 90 preferably so operated as to cause a rapid circulation in the tubes B¹ and B².
- A further advantage in this type of process is the fact that the oil is circulating in the same plane as the heating surface or substantially horizontally. Generally oil 95 treated under pressure for the conversion or cracking of the oil into lower boiling point hydrocarbons is processed in an apparatus in which the oil is passed through successive stages of varied depths, that is the oil passes from one level to another as contrasted with the process herein shown in which the oil is circulated through an 100 apparatus positioned in substantially the same horizontal plane. This horizontal circulation maintains substantially equal depth of the oil and a relatively constant depth in the heating zone wherein the heating is more uniform due to the equal distribution of the liquid. This uniform distribution in heating serves to provide 105 increased vaporization and conversion in the vaporizing chamber, and gives a consequential improved vaporization and higher quality distillate. By the terms independent circulation or local circulation as used in the specification and claims, it is meant that the oil may be circulated independently through either the heating tubes or the distilling tubes. This circulation may be maintained independently in each set of tubes simultaneously or a circulation may be maintained in one set 110 without the other.

I claim as my invention:

1. A process of converting heavy hydrocarbons into lighter hydrocarbons consisting in passing the hydrocarbon in relatively small streams through a heating zone, passing the hydrocarbon from the heating zone in a larger stream through a distilling zone, causing an independent cyclic circulation of the oil in the heating zone, causing an independent cyclic circulation of the oil in the distilling zone, taking off and condensing the vapor from the distilling zone and maintaining the oil under the pressure of the generated vapors during the distillation and condensation.
2. A process of converting heavy hydrocarbons into lighter hydrocarbons consisting in passing the hydrocarbon in relatively small streams through a heating zone, passing the hydrocarbon from the heating zone in a larger stream through a distilling zone, causing an independent cyclic circulation of the oil in the heating zone, causing an independent cyclic circulation of the oil in the distilling zone, taking off and condensing the vapor from the distilling zone and maintaining the oil under the pressure of the generated vapors during the distillation and condensation in excess of 50 pounds to the square inch, and causing the oil to circulate both in the heating and distilling zones in substantially the same horizontal plane.
3. The process of converting heavy into lighter hydrocarbons, comprising heating hydrocarbon oil while passing in a restricted stream through a heating zone, in discharging heated oil from said stream into a distilling zone, in causing an independent cyclic circulation of the restricted stream of oil passing through said heating zone, in taking off vapors from the distilling zone, and in maintaining the oil under superatmospheric pressure during distillation.
4. The process of converting heavy hydrocarbons into lighter hydrocarbons, comprising passing the hydrocarbon through a heating zone, in discharging the same from the heating zone into a distilling zone, in causing an independent cyclic circulation of the oil in the heating zone, and in also causing an independent cyclic circulation of the oil in the distilling zone, in taking off vapors from the distilling zone, and in maintaining the oil in the system under a vapor pressure.
5. The process of converting heavy hydrocarbons into lighter hydrocarbons, comprising passing the hydrocarbon through a heating zone, in discharging the same from the heating zone into a distilling zone, in causing an independent cyclic circulation of the oil in the heating zone, and in also causing an independent cyclic circulation of the oil in the distilling zone, in taking off vapors from the distilling zone, in introducing

regulated quantities of raw oil to the heating zone during the cyclic circulation of oil therein, in returning condensate to said distilling zone, in discharging distillate from the system, and in maintaining the oil under the pressure of the generated vapors within the system.

6. The process of converting heavy hydrocarbons into lighter hydrocarbons, comprising passing the hydrocarbon in streams through a heating zone, in discharging the oil from the heating zone to a distilling zone, in effecting an independent forced cyclic circulation on the oil at times in the heating zone, in causing an independent forced cyclic circulation of the oil at times in the distilling zone, in discharging the vapors from the distilling zone and in maintaining a vapor pressure during distillation of the oil.

7. The process of converting heavy hydrocarbons into lighter hydrocarbons, comprising passing the hydrocarbons in streams through a heating zone, in discharging the oil from the heating zone to a distilling zone, in effecting an independent forced cyclic circulation on the oil at times in the heating zone, in causing an independent forced cyclic circulation of the oil at times in the distilling zone, in discharging the vapors from the distilling zone, in collecting the vapors in a manifold, in passing the vapors from the manifold through coils, and in finally subjecting the same to a condensing action.

8. A process of converting heavy hydrocarbons into lighter hydrocarbons comprising passing the oil in a relatively small stream through a heating zone, discharging the oil from the heating zone to a distilling zone of comparatively larger cross section effecting independent forced cyclic circulations of the oil at times in the heating and distilling zones, subjecting the vapors evolved in the distilling zone to a condensing action, and maintaining a vapor pressure during distillation, said independent circulations in the heating and distilling zones being effected in substantially the same horizontal plane.

9. A process of converting heavy hydrocarbons into lighter hydrocarbons consisting in the passing of hydrocarbon oil in a relatively small stream through a heating zone, discharging the oil therefrom into a distilling zone of relatively greater cross section effecting independent forced local circulations of the oil periodically in the heating and distilling zones, said circulations taking place at substantially the same level and in a substantially horizontal plane, subjecting the vapors evolved in the distilling zone, to a condensing action, and maintaining a vapor pressure during distillation of the oil.

10. A process of converting heavy into heated taking off vapors from the distilling lighter hydrocarbons, consisting in passing zone and causing a forced local recirculation of the oil through the distilling zone the hydrocarbon oil in relatively small withdrawing and condensing the vapors 25 streams through a horizontally disposed evolved in the distilling zone and maintaining coil in a heating zone, in discharging the a controlled pressure in excess of fifty oil therefrom into a distilling zone of substantially greater diameter and located in pounds per square inch upon the oil undergoing substantially the same plane as said heating treatment.
10. A process of converting heavy hydrocarbons into light hydrocarbons, consisting in passing oil to a relatively small coil positioned in a heating zone, directing the heated oil thence to a distilling zone, in taking off the evolved vapors from the distilling zone 30 and in causing a forced local cyclic circulation of the oil through the distilling zone, in condensing the evolved vapors, and in maintaining a superatmospheric pressure on the oil undergoing conversion.
11. A process of converting relatively heavy hydrocarbons into light hydrocarbons consisting in passing oil through a relatively small coil positioned in a heating zone directing the heated oil, thence to a distilling zone, also adapted to be externally 35
- 20 a superatmospheric vapor pressure.
20. A process of converting relatively heavy hydrocarbons into light hydrocarbons consisting in passing oil through a relatively small coil positioned in a heating zone directing the heated oil, thence to a distilling zone, also adapted to be externally a superatmospheric vapor pressure.

CARBON P. DUBBS.
